COLUMN CLAMP

Filed May 22, 1928

Inventor:
Max Anders Eklof,
By *Cheever & Cox* Atty.

UNITED STATES PATENT OFFICE

MAX ANDERS EKLOF, OF CHICAGO, ILLINOIS

COLUMN CLAMP

Application filed May 22, 1928. Serial No. 279,766.

My invention relates in general to column clamps and has more particular reference to an improved clamp for concrete columns which has certain features of novelty and 5 advantage which will hereinafter more fully appear.

One of the objects of my invention is to provide a column clamp which may be quickly and easily assembled in clamping position 10 about a column, which may be economically manufactured, which will firmly hold the sides of the column in position and which will not slip when being detached.

Another important object of my invention 15 is to provide a column clamp of novel design and arrangement wherein the parts are arranged to allow of easy assembly no matter how much concrete may have fallen and hardened upon the members forming the 20 clamp.

Numerous other objects and advantages 25 will be apparent as my invention is more fully understood from the following description which, taken in connection with the accompanying drawings, discloses a preferred embodiment.

Referring to the drawings:

Figure 1 is a perspective view of my improved column clamp as assembled around a 30 column form;

Figure 2 is a side view of a member, a plurality of which are adapted to form the improved column clamp of my invention;

Figure 3 is a top plan view of the parts 35 illustrated in Figure 1;

Figure 4 is a plan view illustrating a manner in which the members of my column clamp may be slotted;

Figure 5 is a plane view illustrating another manner in which the members of my 40 column may be slotted;

Figure 6 is a side view of one end of a modified bar, a plurality of which are adapted to form my improved column clamp, showing the relative position of adjacent bars of the column clamp while being assembled; and

Figure 7 is a similar view illustrating the relative position of two adjacent bars when in 50 assembled position.

To illustrate my invention I have shown on the drawings a column clamp consisting of four bars 11, rigid and preferably formed of some durable metal such as steel or wrought iron. Each bar is provided at one end with an open loop 13 which is formed by bending up the end of the bar so that the end portions 15 extend parallel and in spaced relationship with the body of the bar. In the body of each bar, extending from the straight end to adjacent the bent end I form a plurality of relatively long slots or apertures 17 which in the illustrated embodiment are formed in two rows, the slots of one row being staggered with respect to the slots in the other row. These slots are adapted to accommodate wedges 19 formed of strips of steel or similar material and which are adapted to be driven into the slots behind the outer edge of the adjacent bar, when the clamp is in assembled position as shown in Figure 1, in order to tighten the clamp about the column to which it is applied. The slotted bars and wedges are described in detail in my co-pending application Serial No. 187,201 filed the 28th day of April, 1927, now Patent No. 1,674,280, June 9, 1928.

As illustrated in Figure 1, my column clamp is adapted to be applied to a rectangular form for a concrete column. The form illustrated comprises a plurality of boards 21 arranged to form a rectangular hollow tube into which the concrete may be poured, and the column clamp is arranged about this form by placing a bar 11 transversely across each side of the rectangular form, and arranging the looped end of each bar in embracing relationship with the slotted portions of the adjacent bar, the slotted end of the adjacent bar extending outwardly beyond the outer edge of the loop end. In order to tighten the clamp upon the form, the wedges 19 are driven into the slots adjacent the outer edge of the bar which results in the looped end of each bar being forced axially along the slotted body of the adjacent bar about which it is looped, and inwardly against the sides of the form, the staggered arrangement of the slots 17 permitting two wedges to be used alternately to tighten the clamp members to 100

any desired position within the range of the slotted portion of the body of the bars. The bars are made of substantially wide stock so that the base of the loop which engages the outer edge of the adjacent bar will have an aligning effect upon the adjacent embraced bar.

A hand screw 23 is arranged in the bent end portion 15 of each bar and carries an inner clamping member in position to engage the body of the embraced bar when the latter is arranged within the loop. This construction is illustrated clearly in Figure 2.

When all the pressure bars are located in clamping position about the column form, the hand screws on all the bars may be tightened. The provision of these manually operable handscrews is particularly adapted to prevent accidents when the column clamp is being removed from clamping position after it has served its purpose. After the form has been filled with concrete and the concrete has hardened, it is necessary to strip off the column clamp and form therefrom. This is done by knocking out the wedges 19. The workman assigned to strip the column clamps from a finished column, when removing the higher clamps, usually stands upon the projecting ends of the bars of a lower clamp and supports himself, while knocking out the wedges, by holding on to the projecting ends of the bars of the clamp being removed. There is considerable pressure outwardly upon the bars of the column clamps after the concrete has been poured and it frequently happens that when the wedges are knocked out of the slots, the looped end of a bar will be forced outwardly by this pressure, and will push the workman's hand from the projecting end to which he is clinging, or will crush his hand. This is particularly dangerous where the work is being done at considerable heights for the workman may easily lose his balance and fall to the ground. In the past, this circumstance has led to a large number of accidents. By providing the hand screws or clamps 23 the danger of this sudden movement of the bars upon the removal of the wedges is considerably reduced if not obviated entirely. During the pouring operation considerable quantities of cement fall upon the upper surface of the bars and hardens there. This deposit, together with the clamping action of the hand screws, prevents any sudden movement of the bars upon the removal of the wedges.

For large columns I contemplate the use of a modified form of looped end as illustrated in Figures 6 and 7 of the drawings. In this modification the end of each bar is arranged in the form of a closed loop which is formed by bending the end of the loop downwardly and thence rearwardly parallel with the body of the bar to form a portion 25 spaced from the body of the bar a dis-

tance slightly greater than the thickness of the slotted portion of the adjacent bar. From the end of the portion 25 the side of the loop is off-set downwardly as at 27 and thence forwardly to provide a portion 29 parallel to and spaced from the body of the bar a distance equal to substantially twice the thickness of the slotted portion of the adjacent bar. Thereafter the side of the loop is off-set inwardly as at 31 and finally 75 extends in engaging relationship with the body of the bar being secured thereto at 33. This construction provides a loop having a wide portion 35, a narrow portion 37 and the off-set portion 27 which provides a shoulder 39 for a purpose to be hereinafter more fully described.

For columns of medium size, the looped construction shown in Figure 2 is deemed adequate both for the purpose of aligning 85 the pressure bars and for the prevention of accidents and also to enable operators using this form of clamp to work more rapidly than has been possible with column clamps heretofore provided. It is apparent that the 90 mouth or opening of the open loop is formed considerably larger than the width of the body of the adjacent bar embraced by the loop. It will be understood, therefore, that the body of the adjacent bar may be arranged in the loop quickly and easily in spite of whatever concrete may have been deposited upon this bar. For larger columns it is desirable to utilize a closed loop in order to take advantage of the increased 100 strength inherent in this type of loop. In the embodiment illustrated in Figures 6 and 7 the wider portion 35 of the loop is adapted to receive the end of the adjacent bar with sufficient tolerance to provide for any 105 cement 41 which may have been deposited thereon. The end of the adjacent bar is thus slid longitudinally into the wider portion of the loop as illustrated in Figure 6 and is then slid laterally into the narrow 110 portion 37 of the loop as illustrated in Figure 7, the shoulder 39 operating, during such lateral movement, to strip off the cement deposit from the lower side of the bar in order to permit the same to snugly engage 115 within the narrow portion 37. Since the narrow portion 37 snugly embraces the body of the adjacent bar arranged therein, it will be apparent that when the wedges 19 are removed from the slots in stripping off the 120 column clamp, that this snugness of fit together with whatever cement may have been deposited upon the the body of the bar adjacent the loop, will prevent the sudden displacement of the parts and will hence prevent the consequent danger, by way of accidents, to the workman.

It is thought that my invention and its numerous advantages will be apparent from the foregoing description, and it is evident 125

that numerous changes may be made in the form, construction and arrangement of the various parts without departing from the spirit and scope of my invention or sacrificing any of its material advantages, the forms herein described being merely preferred embodiments of the invention.

Having thus described my invention what I claim as new and desire to secure by Letters Patent is:

- 10 1. In a column clamp comprising a plurality of slotted bars each having a looped end adapted to embrace the slotted portion of an adjacent bar, wedges adapted to seat in the slots to secure the adjacent bars in engaged position about a column, and means including a widened portion of said loop and a portion adapted to closely engage the body of the adjacent bar whereby to temporarily 15 secure the parts in relative position when the wedges are removed.
- 20 2. In a column clamp comprising a plurality of slotted bars and wedges for securing said bars together about a column, a looped portion forming a relatively wide portion and a relatively narrow portion formed at one end of said bar in position to embrace the body of an adjacent bar, said wide portions being of a size to permit the adjacent bar to be easily 25 slid axially into the loop notwithstanding the deposit of cement and the like which forms on such bars when in use, and said narrow portions being of a size such as to closely embrace the body of the bar so that the latter may be 30 slid laterally into the narrow portion after being arranged in the wide portion as aforesaid.
- 30 3. In a column clamp comprising a plurality of slotted bars and wedges for securing said bars together about a column, a looped portion forming a relatively wide portion and a relatively narrow portion formed at one end of said bar in position to embrace the body of an adjacent bar, said wide portions being of a size to permit the adjacent bar to be easily 35 slid axially into the loop notwithstanding the deposit of cement and the like which forms on such bars when in use, and said narrow portions being of a size such as to closely embrace the body of the bar so that the latter may be 40 slid laterally into the narrow portion after being arranged in the wide portion as aforesaid.
- 40 4. In a column clamp comprising a plurality of bars provided with means formed and arranged for securing them about a column, a looped portion formed in an end of a bar by bending the end thereof back upon itself and securing the free end of the bar to the body thereof to form a loop, having a 45 wide portion and a narrow portion adapted

to closely embrace the sides of a bar arranged therein.

5. A column clamp comprising a plurality of rigid members arranged to embrace a column and having adjacent overlapping end portions, one of said end portions being provided with a series of overlapping longitudinal slots, each adapted to receive a wedge whereby the adjacent overlapping portion may be urged towards the column as the wedge is driven into the slot, and means for temporarily securing said overlapping end portions whereby to prevent relative movement between the parts when one of said wedges is removed in stripping the column 70 75 clamp.

6. A column clamp comprising a plurality of substantially rigid members adapted to embrace a column and having adjacent overlapping portions, one of said overlapping portions being provided with overlapping linear slots each adapted to receive a wedge in position to engage the adjacent overlapping portion and force the same towards the column as the wedge is driven into the slot, 80 85 said slots being arranged in spaced relationship in parallel rows, and means for temporarily securing said overlapping end portions whereby to prevent relative movement between the parts when one of said wedges is removed in stripping the column clamp.

7. A column clamp comprising a plurality of substantially rigid members adapted to embrace a column and having adjacent overlapping portions, one of said overlapping portions being provided with overlapping linear slots each adapted to receive a wedge in position to engage the adjacent overlapping portion and force the same towards the column as the wedge is driven into the slot, 90 95 said slots being arranged in spaced relationship in parallel rows, and means for temporarily securing said overlapping end portions whereby to prevent relative movement between the parts when one of said wedges is removed in stripping the column clamp.

7. A column clamp comprising a plurality of substantially rigid members adapted to embrace a column and having adjacent overlapping portions, one of said overlapping portions being provided with overlapping linear slots each adapted to receive a wedge in position to engage the adjacent overlapping portion and force the same towards the column as the wedge is driven into the slot, 100 105 said slots being arranged in spaced relationship in parallel rows, and means for temporarily securing said overlapping end portions whereby to prevent relative movement between the parts when one of said wedges is removed in stripping the column clamp.

8. A column clamp comprising a plurality of substantially rigid members adapted to embrace a column and having adjacent overlapping portions, one of said overlapping portions being provided with overlapping linear slots each adapted to receive a wedge in position to engage the adjacent overlapping portion and force the same towards the column as the wedge is driven into the slot, 110 115 successive slots being in off-set relationship and each slot opening at its upper end into the lower end of the succeeding off-set slot.

9. A column clamp comprising substantially rigid members arranged to embrace a column and having adjacent overlapping end portions, one of said portions being provided with a plurality of elongated slots arranged in parallel adjacent lines, the slots in one line being staggered with respect to the slots in the other line, the slots in adjacent lines opening into each other.

10. A column clamp comprising substan-

125

130

tially rigid members arranged to embrace a column and having adjacent overlapping end portions, one of said portions being provided with a plurality of elongated slots arranged in parallel adjacent lines, the slots of adjacent lines being arranged in overlapping relationship, and each slot comprising a multiple opening adapted to receive one or more wedges in staggered relationship.

- 10 11. In a column clamp of the class described, a plurality of rigid bars for embracing a column, wedges for securing said bars in embracing position, said bars being formed at one end with a loop by bending the end thereof back upon itself and having a plurality of overlapping linear slots for receiving said wedges in position to engage the adjacent overlapping bar and force the same toward the column as the wedge is driven
15 into the slots, and a hand clamp arranged in said loop for temporarily securing the bars in embracing position when the wedges are removed.

20 In witness whereof, I have hereunto sub-
25 scribed my name.

MAX ANDERS EKLOF.
